SHIRT

Charles Solomon, Thomasville, Ala.

Application October 21, 1954, Serial No. 464,051

1 Claim. (Cl. 2—115)

This invention relates to improvements in shirt and shirt type garments and to the construction thereof.

More particularly, the present invention proposes the construction of an improved pullover type shirt with a front member having a straight free top edge adapted to extend across the chest of the wearer with spaced buttons on the front member adjacent the top edge adapted to fit buttonholes in the end portions of the collar of the shirt so that the collar end portions can be buttoned down over the free straight top edge of the front member to close the collar of the shirt.

Still further, the present invention proposes forming the shirt with a back connected shoulder member having front edge portions adapted to underlie the top edge of the front member with buttons on such front edge portions and buttonholes in the front member adjacent its top edge so that all these members and the collar end portions may be separate for ease in putting on the shirt or for hot weather comfort and removably connected together after the shirt is on.

As a further object, the present invention proposes constructing the shirt with snap fastener elements on the front member and on the front edge portions of the shoulder member removably to hold these members together and with buttons on the front member and buttonholes in the end portions of the collar removably to hold the collar to the front member over the top straight free edge of the front member.

Another object of the invention proposes forming the shirt with one front edge portion of the shoulder member permanently secured to the front member adjacent the top edge of the front member and providing a spaced row of buttons on the front member to button the collar ends to at different angles of divergence.

For further comprehension of the invention, and of the objects and advantages thereof, reference will be had to the following description and accompanying drawings, and to the appended claim in which the various novel features of the invention are more particularly set forth.

On the accompanying drawings forming a material part of this disclosure:

Fig. 1 is a front view of the upper portion of a person wearing a shirt constructed and arranged in accordance with the present invention.

Fig. 2 is a fragmentary view of the upper portion of the shirt shown in Fig. 1.

Fig. 3 is a view similar to Fig. 2 but showing the collar open.

Fig. 4 is an enlarged sectional view taken on line 4—4 of Fig. 2.

Fig. 5 is an enlarged sectional view taken on line 5—5 of Fig. 2.

Fig. 6 is a view similar to Fig. 2 but illustrating a modification of the present invention.

Fig. 7 is an enlarged sectional view taken on line 7—7 of Fig. 6.

Fig. 8 is a view similar to Fig. 7 but showing the snap fastener elements apart.

2

Fig. 9 is a view similar to Figs. 2 and 6 but illustrating a further modification of the invention.

Fig. 10 is an enlarged sectional view taken on line 10—10 of Fig. 9.

5 The pullover type shirt, in accordance with the first form of the invention illustrated in Figs. 1 to 4, inclusive, is designated generally by the reference numeral 15.

Shirt 15 has a front member 16 and a back member 17 with a shoulder member 18 extending from the back member 17.

Front and back members 16 and 17 have side edge connected portions 19 and armhole portions 20. Sleeves 21 and 22 are disposed in the armhole portions 20 and connected by stitches 23 to the front and back members 16 and 17 and to the shoulder member 10. Front member 16 has a bottom edge 24 and a top straight edge 25 which is connected at its ends 26 and 27 to the sleeves 21 and 22 and shoulder member 18 but which is free therebetween.

Shoulder member 18 has spaced front edge portions 28 and 29 adapted to underlie the top edge 25 of front member 16. Preferably, the shoulder member 18 is formed integral with back member 17 but it may be made as a separate part and stitched to the back member. Buttons 30 and 31 are secured to the front edge portions 28 and 29 respectively as by thread 32, and the front member 16 is provided with buttonholes 33 and 34 adjacent to and spaced from the top edge 25 removably to receive the buttons 30 and 31 respectively. Buttons 30 and 31 on the front edge portions 28 and 29 of shoulder member 18 and buttonholes 33 and 34 in the front member 16 provide coacting fastening means removably to connect the members 16 and 18 together adjacent the top edge 25 of member 16.

A collar 35 is secured to the shoulder member 18 by stitching 36. Collar 35 has two spaced end portions 37 and 38 which may be rounded tips as shown or pointed tips or other well known collar styles.

Buttonholes 39 and 40 are provided in the end portions 37 and 38 respectively removably to fasten the collar 35 to buttons 30

40 and 31 on the front edge portions of the shoulder member 18 after front member 16 has been secured to the same buttons by its buttonholes 33 and 34, as is shown in Fig. 2.

Additional spaced buttons 41 and 42 are provided on the front member 16 between buttonholes 33 and 34 and aligned therewith adjacent to and spaced from the top edge 25 of the front member. Buttons 41 and 42 are

45 identical in size and shape to buttons 30 and 31 so that collar 35 may be secured by its buttonholes 39 and 40

to either buttons 30 and 31 as shown in Fig. 2 or to buttons 41 and 42 as shown in Fig. 1 or to neither as shown in Fig. 3.

Reinforcing bands 43 and 44 may be provided on the front member 16 along the top edge 25 and similar reinforcing bands 45 and 46 may be provided on shoulder member 18 beneath buttons 30 and 31.

To put on the shirt 15 or for hot weather comfort, all buttons may be unbuttoned as shown in Fig. 3. Once the shirt is on, however, the collar ends 37 and 38 may be

60 buttoned to buttons 30 and 31 to provide a wide spaced or "open" collar or may be buttoned to the buttons 41 and 42 to form a more "closed" collar. The collar ends in each such case will extend over the free top edge 25 of front member 16 and hold it down.

The modification of the invention illustrated in Figs. 6, 7 and 8 is characterized by the provision of a pullover shirt 50 having front and back members 51 and 52, shoulder member 53 and sleeves 54 and 55. The front member 51 has a straight top edge 56 which is secured

65 only at its ends 57 and 58 to sleeves 54 and 55 and shoulder member 53. Shoulder member 53 has front edge portions 59 and 60 adapted to underlie the top edge 56

of front member 51. Snap fastener elements 62 are secured to the front edge portions 59 and 60 of the shoulder member 53 and mating snap fastener elements 63 are secured to the front member 51 adjacent the top edge 56 thereof. Buttons 64 and 65 are secured to the front member 51 and disposed on top of the snap fastener elements 63.

Additional buttons 66 and 67 are provided on the front member 51 aligned with and disposed between buttons 64 and 65. A collar 68 is secured to the shoulder member 53. Collar 68 has end portions 69 and 70 with buttonholes 71 and 72 adapted to fit the buttons 64, 65, 66 and 67.

The modification of the invention illustrated in Figs. 9 and 10 is characterized by the provision of a pullover type shirt 75 similar to shirt 50 described above and having similar parts given similar reference numerals but primed to distinguish the figures. Shirt 75 however, has one of the front edge portions, front edge portion 59', of its shoulder member 53' stitched to the front member 51' by stitching 76 along the top edge 56' of front member 51'. No snap fastener elements are provided therefor on this side of the shirt. The snap fasteners on the other side permit the collar to be opened wide enough to get the shirt on when it is pulled over the wearer's head.

With this arrangement it is possible to open only one of the buttons for removing or getting the shirt on or off the wearer.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new and desire to secure by United States Letters Patent is:

A pullover type shirt comprising a front member, a

back member, said members having side edge-connected portions and armhole portions, said front member having a straight top marginal edge, a shoulder portion integral with the back member and extending forwardly therof, the forward edge of said shoulder portion being unattached, a portion of said forward edge being shaped to constitute a semi-circular neck opening, the remaining portions of said forward edge extending laterally from the front ends of the neck opening in a curved line to points forwardly of the top marginal edge of the front member thereby providing closable gaps communicating with the neck opening and extending as reentrant slits laterally in both directions from the neck opening, the top marginal edge of the front member loosely overlapping the unattached front curved edge portions of the shoulder portion, a folded collar secured to the semi-circular neck opening of the shoulder portion, said collar having diverging pointed ends forming an inverted V-shaped front end, and fastening members spaced along and adjacent the meeting edges of said gaps for removably securing the overlapped meeting edges for closing said gaps, the top marginal edge of the front member being so positioned as to traverse approximately the apex of the collar opening's inverted V-angle when the gaps are closed, said collar having openings in its pointed ends adapted to receive the fastening members on the meeting edges of the gaps for securing said pointed ends in selected positions along the top marginal edge of the front member.
